[57] CLAIM

The ornamental design for a golf putter head and shaft, as shown and described.

DESCRIPTION

FIG. 1 is a perspective view of the golf putter head and shaft embodying my new design invention wherein the shaft is shown fragmentarily for convenience of illustration.

FIG. 2 is a top plan view thereof;

FIG. 3 is a front elevational view thereof;

FIG. 4 is a side elevational view thereof;

FIG. 5 is a rear elevational view thereof and

FIG. 6 is a bottom plan view thereof.

The end of the shaft is omitted in FIGS. 2-6 of the drawings for convenience of illustration.
